CLAMP DEVICE

Herman H. Helbush, Los Angeles, and Elmer L. Lipp, Glendale, Calif., assignors, by mesne assignments, to said Helbush

Application August 23, 1941, Serial No. 408,100

1 Claim.

(Cl. 85—5)

This invention relates to clamp devices for temporarily holding together perforated sheets, with their perforations in alignment, preparatory to riveting or the like.

Devices now in use for such purposes generally comprise a clamp element which has a clamping pin slidably mounted in a housing, the pin being inserted through the aligned holes in the superposed sheets. The pin usually has an enlarged or deformed outer end portion which, after being inserted through the aligned holes, bears against the bottom sheet and a coil spring, bearing at one end against the head of the pin and at its other end against the housing, urges the pin inward of the housing, thus clamping the superposed sheets between the enlarged or deformed end of the pin and the outer end of the housing. The coil springs used for this purpose are necessarily relatively strong and in order to compress them while applying the clamp, considerable pressure must be applied to the end of the pin. In fact this pressure is so great that unless the clamp is absolutely centered in the applying tool, it often flies out when pressure is applied to compress the spring, resulting in injury to workmen. In aircraft factories, for instance, where such clamps are being extensively used, this shortcoming of clamps now in use constitutes a distinct hazard.

One of the principal objects of this invention, therefore, is to provide means for removing this hazard by automatically locking the clamp in the applying tool as the clamp is applied.

Still further advantages are inherent in our invention and how those, as well as the objects hereinabove specifically mentioned, are attained will become clear from the following detailed explanation of a presently preferred embodiment, for which purposes reference will be made to the accompanying drawing, in which:

Fig. 1 is a view partly in medial section and partly in elevation;

Fig. 2 is an enlarged fragmentary section;

Fig. 3 is a section taken on line 3—3 of Fig. 2;

Fig. 4 is a section taken on line 4—4 of Fig. 2;

Fig. 5 is a plan view taken on line 5—5 of Fig. 1;

Fig. 6 is a fragmentary side elevation of a variational form; and

Fig. 7 is a fragmentary view taken on line 7—7 of Fig. 6.

In general, we carry our invention into practice by providing opposed surfaces or means on the clamp element and the clamp applying tool which

interlock by virtue of relative movement between the clamp element and the applying tool.

Referring now to the drawing, Figs. 1 to 5, inclusive, we show a clamp element C and a clamp applying tool T. The tool T, which is more particularly described and claimed in our copending application Serial Number 411,878, filed September 22, 1941, which application matured into Patent No. 2,296,439, comprises a pistol-shaped body

10 formed by companion side plates 10 providing a handle portion 11 and a barrel portion 12. Longitudinally in the barrel, we mount a channel iron track member 15 which is transversely slotted at 16 to receive the outer end of the body. 15 At the outer end, the side walls 17 of the track member 15 curve outwardly and upwardly and a curved liner 20 is welded to the curved side walls 17 to provide a semi-circular cradle 21 to receive the clamp C.

20 An oppositely disposed channel iron member 25 is slidably mounted in the barrel along the track 15, member 25 having an outer end wall 26 to which a plunger 27 is secured by extending reduced end 27a through a hole in wall 26 and then heading it at 27b. A channelled trigger 30 is pivotally mounted in the body by pin 32. So that member 25 and plunger 27 may be slidably moved upon manual movement of the trigger, a link 35 is pivotally secured at one end to member 25 by pin 36 and likewise secured at its other end to the upper end of the trigger by pin 37. A coil spring 38, secured at one end to bracket 39 and at its other end to the trigger, returns the trigger to inoperative position as shown by full lines 35 in Fig. 1. Rivets 40, 41 and the headed ends of pin 32 hold the body plates 10 together.

40 Applying tools of other specific structures may be used so long as they are of a structure capable of embodying the clamp locking feature to which this present application is more particularly directed. In incorporating our invention in the applying tool just described (see Fig. 1), we concave the outer end 45 of plunger 27 to receive the convexed end of clamp C to be described and provide a tapered undercut 46 along the inner surface of shoulder 47 of liner 20, for the purpose of receiving an oppositely beveled portion of the clamp C to be described.

The clamp C which we have selected to illustrate an application of our invention is more particularly described in United States Letters Patent Number 2,266,929, dated December 23, 1941. It includes a round, hollow body 50 having an annular channel 51 providing a shoulder 52. The end wall 54 has a hole therethrough

to slidably pass a split retaining pin 55. An outwardly curved end plate 57 is secured as by crimping on the outer end of the body 50 and has a central hole to pass the pin 55, a T-shaped spreader 56, shown in elevation in Fig. 2, being positioned between the legs of the split pin and having its cross member 56a floatably mounted in the space between the inner surface of plate 57 and the outer end of wall 54. Pin 55 is rotatably mounted in sleeve 60, having its headed end 55a mounted in a recess in the convexed end 65 of the sleeve.

Shoulder 52 of the clamp has an annular undercut 52a tapered oppositely to the tapered undercut 46 of tool T. Thus, in operation, the clamp C is placed longitudinally in the curved cradle or socket 21, with shoulder 47 in the channel 51, and as the trigger 30 is manually moved towards the handle, the plunger 27 moves against the adjacent end 65 of clamp pin 55, the convexed end 65 fitting into the concaved end 45 of the plunger. Outward movement of the plunger against the spring-pressed pin 55 causes the undercut surface 52a to engage the oppositely tapered undercut 46 of the tool. Since the inter-engaging undercuts 52a and 46 are curved, no radial movement of the clamp with respect to the tool is possible.

In Fig. 6, we illustrate a variational form of clamp applying tool embodying means for locking the clamp therein. This tool is of the pliers type, having two pivotally connected arms 80, 81.

Arm 80 has a concaved socket 80a to receive the convexed end 65 of the clamp C and arm 81 is bifurcated at its outer end to provide a semi-circular cradle 81a having a tapered front surface 81b which fits into the undercut 52a of the clamp. In operation, the clamp C is placed in the cradle 81a and as the arms 80, 81 are moved together the undercut 52a of the clamp engages over the oppositely tapered surface 81b of the cradle to lock the clamp in the applying tool.

While, for the purposes of making our invention understood, we have resorted to specific structural details, we wish it understood that our invention, in its broader scope as defined by the appended claim, is susceptible of various modifications and adaptations and is not confined to the details described.

We claim:

A skin clamp adapted for use in conjunction with a clamp-operating tool, comprising a cylindrical body, a retaining pin reciprocally mounted in the body for protraction and retraction through the outer end thereof, a spring opposing protractive movement of the pin, and an annular shoulder on the body, said shoulder presenting an annular undercut opening towards the outer end of the body whereby to inter-engage with a part of the clamp-operating tool during protraction of the pin.
